UNITED STATES PATENT OFFICE.

KATHERINE J. MANEY, OF MUKWONAGO, WISCONSIN.

IRON-HOLDER.

1,218,098.

Specification of Letters Patent.

Patented Mar. 6, 1917.

Application filed November 20, 1916. Serial No. 132,334.

To all whom it may concern:

Be it known that I, KATHERINE J. MANEY, a citizen of the United States, and resident of Mukwonago, in the county of Waukesha and State of Wisconsin, have invented certain new and useful Improvements in Iron-Holders; and I do hereby declare that the following is a full, clear, and exact description thereof.

10 The present invention relates to new and useful improvements in holders for irons or other articles more particularly of that type adapted for securement to an ironing board or table to project outwardly of the 15 edge thereof.

It is primarily the object of the present invention to provide as an article of manufacture a holder of this nature which comprises a structure of maximum simplicity 20 consistent with a desired degree of strength and convenience in use.

A further object resides in the provision of a support member which may be attached to an ironing board or table in such manner 25 as to either project from the board or table or to swing to lie within the confines thereof without the necessity of adjusting the attaching means of the holder thereto.

A still further object resides in the provision 30 of a holder of the present nature which may be folded to occupy a minimum space when not in use.

With the above and other objects and advantages in view the invention resides more 35 particularly in the novel combination, formation and arrangement of parts herein-after described and pointed out in the appended claim.

In the drawings: 40 Figure 1 is a plan view of my improved holder secured to and projecting from the edge of an ironing board.

Fig. 2 is a vertical sectional view therethrough on the line 2—2 of Fig. 1.

45 Referring now more particularly to the accompanying drawings, the holder comprises a spider shaped body plate 5 at the free ends of the legs of which is formed a rim 6 corresponding in shape to a desired 50 size of iron and provided with an upstanding retaining flange 7 at its outer periphery. As shown more particularly in Fig. 2, the top face of the rim 6 is offset upwardly

from the spider, and thus may be machined or otherwise rendered smooth so as not to injure the face of the iron, whereby said 55 face of the iron is held from possible contact which might injure it, without the necessity of machining the entire surface of the body plate, it being appreciated that the 60 irons are made of relatively soft metal and that a desired smoothness of their faces is essential.

The longitudinally disposed spider arms are intermediately enlarged at 8 and countersunk in these enlarged portions are the 65 heads of bolts 9 passed therethrough, and pivotally passed through the ends of a pair of links 10. The other ends of these links are provided with apertures 11 for the 70 reception of a securing bolt 12 and one of the links is preferably offset at said other end to provide for their lapped relation to receive the bolt 12.

This securing bolt is also passed through 75 the ironing board 13 or other support, and threadedly engaged on the bolt is a wing nut 14. The holder being thus pivotally secured to the ironing board, it may project therefrom as shown in the drawings, or may 80 be swung to lie inwardly of the board. Upon detachment of the bolt 12, it is noted that the links 10 may swing to lie entirely within the confines of the body of the holder to economize space when the device is not in 85 use. Inasmuch as the load strain of the holder is distributed from the edge of the iron seating rim 6 to the outer ends of the links, a maximum strength is provided consistent with the material employed. 90

What is claimed is:

As an article of manufacture an iron holder comprising a body plate, a pair of links pivotally connected with the body at longitudinally spaced portions thereof, and 95 a securing bolt passed through the other ends of the links and adapted to pass through a support.

In testimony that I claim the foregoing I have hereunto set my hand at Mukwonago, 100 in the county of Waukesha and State of Wisconsin, in the presence of two witnesses.

KATHERINE J. MANEY.
